Fred C. Fischer,

By *F. G. Fischer*,
Attorney.

UNITED STATES PATENT OFFICE.

HENRY G. TRIMBLE, OF KANSAS CITY, MISSOURI.

FIRE BOX.

Application filed August 3, 1925. Serial No. 47,911.

My invention relates to fire-boxes for use in fireplaces of the type associated with chimneys and mantels, and one object is to provide a structure of this character consisting of sections which can be installed at a minimum expenditure of time, labor and cost.

A further object is to provide a durable structure of this character which can be readily installed without the aid of skilled workmen and is of such shape and proportions as to insure the escape of the smoke, gases and other products of combustion to the chimney instead of into the room containing the fireplace, as frequently occurs where the fire-box is built of brick and improperly shaped and proportioned.

In order that the invention may be fully understood, reference will now be had to the accompanying drawings, in which:

Fig. 1 is a front elevation of the fire-box.

Fig. 2 is a vertical central section on line 2—2 of Fig. 1.

Fig. 3 is a plan view of the fire-box.

Fig. 4 is a horizontal section on line 4—4 of Fig. 1.

In carrying out the invention, I employ a base 2 which tapers towards its rear margin and is provided adjacent to its side margins with grooves 4 to receive the lower ends of two side wall slabs 6, which are provided at their forward upper corners with offsets 8 in which a lintel 10 is seated. The base 2 has an opening 5 normally closed by a pivotal lid 7 and through which ashes accumulating on said base 2 may be discharged into an underlying ash pit with which most cellars are provided.

The lintel 10 spans the upper forward portion of the fire-box and is provided at its under side with rearwardly converging grooves 12 to receive the upper forward portions of the margins of the side wall slabs 6. A longitudinal recess 13 is provided in the rear portion of the lintel 10 for directing smoke to the chimney (not shown) instead of permitting it to escape into the room containing the fire-box.

The rear portion of the fire-box is closed by a back wall consisting of slabs 14 and 16, which latter slopes forwardly towards its upper margin and is seated at its lower margin upon the slab 14. The slab 14 is seated in a groove 18 formed in the rear portion of the slab 2 and communicating with the rearwardly converging grooves 4. The

back wall slabs 14 and 16 are firmly secured to the rear margins of the side wall slabs 6 by suitable means such as stud bolts 20 and 22, respectively.

The upper portion of the fire-box is covered by the lintel 10 and a hood 24 which latter is curved upwardly and rearwardly and is provided at its rearwardly converging sides with marginal flanges 26 which rest upon the upper margins of the side wall slabs 6 to which it is secured by suitable means such as stud bolts 28. The front margin of the hood 24 is seated in a recess 30 extending longitudinally of the rear upper portion of the lintel 10.

The rear portion of the hood 24 has a flue or opening for the escape of the products of combustion and which is controlled by a damper 32 rockably mounted in a groove 34 in the upper margin of the back slab 16. The damper 32 is controlled by a pivotally connected ratchet bar 36 which may be reached from the inner front portion of the fire-box. The ratchet bar 36 is adapted to be held at any point of its adjustment by a U-shaped bolt 38 secured to the upper portion of the hood 24.

In practice the fire-box can be readily set up by unskilled workmen, the chief care being to get the base 2 properly positioned. The side wall slabs 6 are then placed in position, the grooves 4 acting as guides for proper placement of said slabs 6. The lintel 10 is then seated in the offsets 8 and its grooved portions 12 coact with the grooved portions 4 of the base 2 in firmly holding the side slabs 6 in upright position. The back wall slabs 14 and 16 are next placed in position, after which assembly of the fire-box is completed by placing the hood 24 in place. After the fire-box has been assembled as above described it may be reinforced by laying one or more courses of brick or stone against the outer surface of the side wall slabs 6 and the rear wall slabs 14 and 16.

Preferably, all excepting the metal parts of the fire-box are constructed of fire clay which can be readily molded into shape while in a plastic condition and then burned in a kiln.

From the foregoing description it is apparent that I have provided a fire-box embodying the advantages herein shown and described, and while I have shown the preferred embodiment of the invention I reserve the right to such modifications and

changes in the construction, combination and arrangement of parts as properly fall within the spirit and scope of the invention as claimed.

5 Having thus described my invention, what I claim and desire to secure by Letters Patent, is:

A fire-box consisting of a base, a rear wall seated upon said base and having an upper 10 forwardly sloping portion, side walls seated upon said base and having offsets in their

upper forward portions, a lintel seated in said offsets and having a longitudinal recess in its rear portion, an upwardly and rearwardly curved hood resting at its forward 15 portion upon said lintel and having its rear margin spaced above the upper margin of the rear wall to leave an opening, and marginal flanges on said lintel which rest upon the side walls of the fire box. 20

In testimony whereof I affix my signature,
HENRY G. TRIMBLE.
